APPARATUS FOR MAKING LIQUID ZINC FROM BLUE POWDER

Filed Nov. 21, 1923

INVENTOR.

BY *Filip Tharaldsen*

Henry M. J.
ATTORNEY.

UNITED STATES PATENT OFFICE.

FILIP THARALDSEN, OF OSLO, NORWAY.

APPARATUS FOR MAKING LIQUID ZINC FROM BLUE POWDER.

Original application filed November 21, 1923, Serial No. 676,079, and in Norway November 28, 1922.
Divided and this application filed July 12, 1927. Serial No. 205,249.

My present invention relates to an apparatus for making liquid zinc from blue powder according to the process described and claimed in my application for patent Serial 5 No. 676,079, filed November 21, 1923, Patent No. 1,647,381, dated November 1, 1927, of which the present application is a division.

According to said process the blue powder is placed upon a bath of liquid zinc and 10 portions of the liquid zinc are raised above the powder and poured over the latter. Just the same effect of intimate contact is obtained by immersing the blue powder into the liquid zinc.

15 The apparatus I use for carrying out this process consists of a rotatable drum, into which the powder is conveyed and in which molten zinc is supplied. The drum is provided with interior scoop-shaped projections. 20 During the rotation of the drum these scoops will each time they pass down into the liquid zinc immerse a portion of the powder into the zinc bath, thus bringing about intimate contact between this powder 25 and the liquid metal. And when the scoops leave the zinc bath they will lift a portion of liquid zinc above the layer of powder and pour it over the same.

The scoop-shaped projections may be subject to modifications as for instance have a 30 perforated bottom. Or the projections may be so located that between the projections and the adjacent wall of the drum, pockets are formed that have one or more apertures, 35 for instance a longitudinal slot, at their base. In this case the liquid metal, that is lifted above the layer of powder in the drum will run back through these apertures upon the mass of powder below.

40 It is understood that the shape and arrangement of the drum may be modified in several respects. So it may have circular or polygonal section, it may be of cylindrical form or cone-shaped, it may be mounted 45 horizontally or in inclined position and so on, such modifications being within the scope of my invention.

The arrangement above described is illustrated in the accompanying drawing which 50 is a transverse vertical section of an apparatus for carrying out my invention.

The apparatus comprises a drum —a— rotatably mounted on rollers —b— —c—

is the lining of the drum and —d'— the inside projections. —e— is the bath of liquid zinc and —f— the mass of powder resting on the surface of the bath. The arrow indicates the direction of rotation. The drum may be operated intermittently, so that certain quantities of powder and liquid metal 60 are supplied to the drum and this charge worked up, after which fresh quantities of powder and liquid metal are supplied. The drum may however also be operated continuously with continuous supply of powder 65 and continuous discharge of the residues. The pockets formed by projections —d'— are provided with longitudinal slots —d"— near the wall of the drum to permit, as stated above, the liquid which is lifted above 70 the layer of powder to run back through the slots onto the powder being raised by the pockets and back to the powder and zinc in the bottom of the drum.

Each projection forms an angle with a 75 radial line extending from the axis of the drum to the point where the projection joins the periphery. By this relative position of the projection to the periphery the powder is carried by the projection to the top of the 80 drum before it is discharged by gravity to the bottom of the latter.

The drum may work independently of the condenser from which the powder is taken. In many cases it is however very convenient 85 to convey the powder to the drum immediately from the condenser, preferably without exposing powder and zinc to the air in order to avoid oxidation.

I claim:

An apparatus for making liquid zinc from blue powder comprising a rotary drum, a plurality of projections constituting pockets extending inwardly from the inner periphery of the drum, whereby portions of the contents of the drum are raised above the charge on the bottom of the drum before being discharged from the projections during the rotation of the drum, said projections having apertures adjacent their inner edges to permit the passage of the liquid zinc during the upward movement of said projections.

In testimony that I claim the foregoing as my invention I have signed my name.

FILIP THARALDSEN.
